ABSTRACT OF THE DISCLOSURE

Polyester filaments containing therein 0.4—5% by weight of a polyalkylene ether and 0.3—3% by weight of a metal salt derivative, and having fine pores aligned in the direction of the filament axis.

This invention relates to polyester filaments having an improved water-absorbing property which is not degraded by repetition of washing. More specifically, it relates to polyester filaments containing 0.4 to 5% by weight of a polyalkylene ether and 0.3 to 3% by weight of a metal salt derivative and having fine pores aligned in the direction of the filament axis.

The conventional techniques for imparting a water-absorbing property to polyester filaments will be described below.

(A) Attempts to render polyester filaments hydrophilic by copolymerizing a polyester with a polyether compound have been proposed in Japanese patent application publications Nos. 10,336/61, 4,312/64 and 15,095/63, British Patent No. 682,866 specification, and U.S. Patent No. 2,744,087 specification.

However, in accordance with methods proposed in these references it is difficult to impart a sufficient water-absorbing property to polyester filaments without deterioration of their thermal and mechanical properties.

(B) Methods comprising blending a polyether in the dispersed state into a polyester have been known from Japanese patent application publications Nos. 5,214/64 and 14,613/66. However, in accordance with these known methods it is impossible to impart a sufficient water-absorbing property to polyester filaments without deterioration of their thermal and mechanical properties.

(C) A method comprising blending a ring-containing vinyl polymer in a polyester and eluting the blended polymer to thereby form fine pores in the polyester has been known from Japanese patent application publication No. 4,815/66.

However, this method fails to impart a water-absorbing property to polyesters.

(D) In view of the description of Example 2 of the specification of Japanese patent application publication No. 5,214/64 it is presumed that there was obtained a fibrous composition of a polyester containing a polyethylene glycol and having fine pores. In accordance with the teachings of this reference it is possible to impart to polyester filaments a temporary water-absorbing property but the said water-absorbing property is abruptly degraded by repetition of washing. Therefore, the filaments obtained in accordance with the teachings of this reference are of little utility.

(E) A method comprising making a polyalkylene ether and an alkali metal sulfonate derivative present in a polyester has been known from Italian Patent No. 796,237 specification. However, in accordance with this method it is impossible to impart a water-absorbing property to polyester filaments.

2

As results of our researches made with a view to overcoming defects of these prior arts, particularly shortcomings that a sufficient water-absorbing property cannot be imparted to polyester filaments, an attempt to impart a sufficient water-absorbing property to polyester filaments results in deterioration of their thermal and mechanical properties, and that if a water-absorption property is once imparted to polyester filaments, said property is not sufficiently resistant to washing, we arrived at the present invention. Accordingly, a primary object of this invention is to impart to polyester filaments an everlasting and sufficient water-absorbing property without deterioration of their thermal and mechanical properties.

This object of the present invention can be attained by polyester filaments containing 0.4—5% by weight of a polyalkylene ether and 0.3—3% by weight of a metal salt derivative and having fine pores aligned in the direction of the filaments axis.

The "polyester" referred to in this invention is a polyester in which at least 60% of the recurring units is composed of polyethylene terephthalate. For instance, it includes polyethylene terephthalate; copolymers obtained by copolymerizing polyethylene terephthalate with a known dicarboxylic acid component, dihydroxy component or hydroxycarboxylic acid component; polyester blends obtained by melt mixing an ethylene terephthalate homopolymer or copolymer with other homopolyester or copolyester; copolymers comprising an ethylene terephthalate homopolymer or copolymer and containing therein amide, urethane, ether, carbonate or other linkages; a fiber-forming polyester other than polyethylene terephthalate; and a fiber-forming polyester ether.

Of course, the above cited polymers may contain known catalysts, coloration inhibitors, heat stabilizers, antistatic agents, optical whitening agents, antiflaming agents, dyes, pigments and inactive fine particles.

The "polyalkylene ether" referred to in this invention is a polymer whose main chain is composed chiefly of alkylene ether units. For instance, it includes polyethylene oxide, polypropylene oxide, an ethylene oxide-propylene oxide copolymer, a mixture of polyethylene oxide and polypropylene oxide, a polymer derived from tetrahydrofuran, and a polymer derived from 1,3-dioxane. These polymers may have a group —OH, —OR or —O—CO—R (in which R is a monovalent organic group which may be optionally substituted) as the terminal group. Two or more of these terminal groups may be present in the polymer. In addition, a polymer blocked with phosphoric acid or a phosphate may be advantageously used. However, it is not preferable to use a modified polyalkylene ether which is made completely inactive by converting all the terminal groups to —OR groups.

It is preferable that the polyalkylene ether has a number average molecular weight exceeding 4,000. The use of a polyalkylene ether having too low a molecular weight is not preferred because a blend of the polyester and such a low molecular weight polyalkylene ether is inferior in spinnability and drawability.

Of course, the polyalkylene ether may contain known oxidants, catalysts and other additives.

The blending of the polyalkylene ether into the polyester may be performed by any method. For instance, it is possible to add a polyalkylene ether to a polymerization vessel for polyester at the time of initiation of the polymerization, during the polymerization or after completion of the polymerization. It is also possible to blend a polyalkylene ether with the use of an extruder into a polyester pelletized after completion of the polymerization. Further, it is possible to mix a solid polyester with a polyalkylene ether by means of a blender and then melt spin the mixture. Still further, it is possible to melt a poly-

ester and a polyalkylene ether separately and mix the melts by means of a screw just prior to the spinning. In order to attain the object of the present invention it is most preferable to add a polyalkylene ether to a polymerization vessel for the preparation of a polyester after completion of the polymerization, or to melt a polyalkylene ether and a polyester separately and mix the melts with the use of a screw just prior to the spinning.

The "metal salt derivative" referred to in this invention includes derivatives of alkali metal sulfonates, derivatives of metal salts of carboxylic, phosphonic and sulfonic acids, and derivatives of di- or mono-metal salts of phosphoric and phosphorous acids.

These metal salts will be detailed hereinbelow.

The "alkali metal sulfonate derivative" referred to in this invention includes compounds having a so-called surface-activating property, more specifically compounds having a hydrophobic group other than the sulfonic group. It is especially preferable to use a compound having only one sulfonic group at one end of its molecule.

Typical instances of such derivative are sodium dodecylbenzenesulfonate, potassium dodecylbenzenesulfonate, sodium nonylbenzenesulfonate and sodium 3-nonylphenoxypyropanesulfonate. But, the derivative is not limited to these specifically mentioned salts. It is not preferred to use an alkali metal sulfonate derivative having two or more sulfonic groups in the molecule, because such compound is not well blended with a polyester and resulting filaments are likely to have poor properties.

The "metal salt derivative of a carboxylic, phosphonic or sulfonic acid" includes surface-activating compounds containing in the molecule at least one hydrophobic group (which corresponds to the metal salt portion of an acid such as carboxylic acid) and a suitable hydrophobic group such as an alkyl group.

As such salt derivative there are cited following compounds but it is not limited to these specifically exemplified compounds:

- (1) $C_8H_{17}COONa$
- (2) $C_8H_{27}COOK$
- (3) $C_{18}H_{37}COONa$
- (4) $C_{12}H_{25}-O-CH_2COONa$
- (5)
$$\begin{array}{c} O \\ || \\ C_{12}H_{25}-P-ONa \\ | \\ ONa \end{array}$$
- (6)
$$\begin{array}{c} O \\ || \\ C_9H_{19}-\text{C}_6\text{H}_4-\text{C}_6\text{H}_4-P-ONa \\ | \\ ONa \end{array}$$
- (7)
$$\begin{array}{c} O \\ || \\ C_9H_{19}-\text{C}_6\text{H}_4-\text{C}_6\text{H}_4-P-O-Mn \\ | \\ O-Mn \end{array}$$
- (8)
$$\begin{array}{c} O \\ || \\ C_{12}H_{25}-\text{C}_6\text{H}_4-P-OK \\ | \\ OK \end{array}$$
- (9)
$$\begin{array}{c} C_8H_{17}COO \\ | \\ C_8H_{17}COO \\ | \\ Zn \\ | \\ C_8H_{17}COO \end{array}$$
- (10)
$$\begin{array}{c} C_9H_{19}-\text{C}_6\text{H}_4-O-\text{C}_6\text{H}_4-C_9H_{19} \\ | \\ NaO-P-ONa NaO-P-ONa \\ | \\ O \\ | \\ O \end{array}$$
- (11)
$$\begin{array}{c} C_{12}H_{25}-S-O-ONa \\ | \\ O \end{array}$$

5 These metal salt derivatives should not possess an ester-linkage-forming group. In case a metal salt derivative containing an ester-linkage-forming group is used, the water-absorbing property of the resulting polyester filaments is very low, and it tends to impose bad influences on properties of the polyester filaments.

10 So-called surface-activating compounds having in the molecule at least one hydrophilic group (corresponding to the metal salt portion of an acid) and a hydrophobic group such as an alkyl group are preferably used in the present invention as the di- or mono-metal salt of phosphoric or phosphorous acid.

15 Such compounds are used in the form of a mono- or di-metal salt, and those in which the remaining $-OH$ groups of phosphoric or phosphorous acid are converted to alkylaryl ester forms are preferably used. Further, it is preferable to use compounds which are free of ester-linkage-forming groups such as an acid group or hydroxyl group other than the phosphoric acid ester portion. The 20 reason is that such ester-linkage-forming group reacts with a polyester when the mono- or di-metal salt derivative of phosphoric or phosphorous acid is blended into the polyester, resulting in occurrence of an undesirable modification of the polyester.

25 Compounds having the following structures may be applied to this invention, but the mono- or di-metal salt derivative of the phosphoric or phosphorous acid is not limited to these specifically mentioned examples in the present invention.

- 30 (1)
$$\begin{array}{c} ONa \\ | \\ C_{12}H_{25}-O-P-ONa \\ | \\ ONa \end{array}$$
- (2)
$$\begin{array}{c} C_{12}H_{25}-O \\ | \\ C_{12}H_{25}-O-P-OK \\ | \\ C_{12}H_{25}-O \end{array}$$

The blending of the above mentioned metal salt derivative may be performed by any method. It is possible to blend the metal salt derivative into the polyester either together with a polyalkylene ether or separately. The 75

blending may be carried out before the initiation of the polymerization for the preparation of a polyester, during the polymerization, or after completion of the polymerization. The salt derivative may be added to a polymerization vessel or blended by means of an extruder or blender. It is also possible to conduct the blending of the metal salt derivative just prior to the spinning. In the case of a mono- or di-metal salt derivative of phosphoric or phosphorous acid, it is preferable to blend it into the polyester after completion of the polymerization.

The present invention will be detailed by referring to drawings.

FIG. 1 is a microscopic photo illustrating the side of filaments from a blend obtained by incorporating polyethylene glycol into polyethylene terephthalate containing sodium dodecylbenzenesulfonate. The figure illustrates the stage that the polyethylene glycol is aligned in the polyethylene terephthalate along the filament axis. Since the filaments have not fine pores, they take a transparent appearance. FIG. 2 is a microscopic photo illustrating the side of filaments of this invention. As they have fine pores aligned along the filament axis, they possess a non-transparent appearance.

FIG. 3 is an electromicroscopic photo of the filaments of FIG. 1 after they have been dyed with osmium tetroxide (OsO_4) and then dissolved. It is observed that the osmium tetroxide is adsorbed in the polyether portion and that the polyether component is blended in the state extended in the direction of the filament axis.

FIG. 4 is an electromicroscopic photo of filaments of the present invention prepared by eluting the polyether portion from the filaments of FIG. 1, after they have been dyed with osmium tetroxide and then dissolved. In this figure the stripe looks thinner because of the existence of fine interior pores than in FIG. 3.

FIG. 5 is a microscopic photo illustrating the side of polyester filaments from a blend obtained by incorporating polyethylene glycol into polyethylene terephthalate containing a di-sodium salt of nonylbenzenephosphonic acid. FIG. 6 is a microscopic photo illustrating the side of polyester filaments according to this invention.

FIG. 7 is an electromicroscopic photo of polyester filaments of FIG. 5, after they have been dyed with osmium tetroxide and then dissolved. FIG. 8 is an electromicroscopic photo of polyester filaments of the present invention obtained by eluting the polyether portion from polyester filaments shown in FIG. 5, after they have been dyed with osmium tetroxide and then dissolved.

FIG. 9 is a microscopic photo illustrating the side of polyester filaments incorporated with a di-sodium salt of nonylphenolphosphoric acid ester. FIG. 10 is a microscopic photo illustrating the side of polyester filaments of the present invention.

FIG. 11 is an electromicroscopic photo of filaments shown in FIG. 9, after they have been dyed with osmium tetroxide and then dissolved. FIG. 12 is an electromicroscopic photo of polyester filaments of the present invention obtained by eluting the polyether portion from polyester filaments shown in FIG. 9, after they have been dyed with osmium tetroxide and then dissolved.

The "fine pores aligned in the direction of the filament axis" referred to in the present invention indicate pores being present in the filament and having a diameter of 0.01μ to 3μ and a length-to-diameter ratio of at least 5.

As shown in FIGS. 2, 4, 6, 8, 10 and 12, the presence of fine pores is confirmed by observation under an optical microscope or electromicroscope. It is preferable that the ratio of the pore volume to the filament volume is within a range from 0.5 to 10%. In case the pore volume ratio is too small, the intended object of the present invention cannot be attained. On the other hand, in case the pore volume ratio is too great, the mechanical properties of the filaments are lowered.

The formation of fine pores may be performed by any method. For instance, it is possible to adopt a method

comprising treating filaments with warm water or a dilute aqueous alkali solution to thereby elute a blended polyalkylene ether. By such treatment the amount of the polyalkylene ether blended into polyester filaments is decreased, and pores such as shown in FIGS. 2, 4, 6, 8, 10 and 12 are formed in the filaments. In case the amount of the polyalkylene ether is not decreased even by such treatment, the existence of pores such as shown in FIGS. 2, 4, 6, 8, 10 and 12 is not observed.

It is also possible to adopt a method blending into a polyester a polymer incompatible with the polyester such as polyamide and polyolefin in addition to a polyalkylene ether and a metal salt derivative and eluting the blended polymer from the blend with a solvent for said blended polymer.

It is most preferable to adopt a method comprising eluting a part of a blended polyalkylene ether with a dilute aqueous alkali solution, while leaving the remaining part of the polyalkylene ether in the filament-constituting material.

During the formation of fine pores a part of the metal salt derivative is necessary stripped off from the filaments.

The amount of the polyalkylene ether finally contained in the filaments is within a range from 0.4 to 5% by weight, preferably from 1 to 4% by weight.

In case the amount of the polyalkylene ether is too small, the intended object of the present invention cannot be attained. On the other hand, in case the amount of the polyalkylene ether is too large, thermal and mechanical properties of the filaments are lowered.

The amount of the metal salt derivative finally contained in the filaments is within a range from 0.3 to 3% by weight, preferably from 0.3 to 2.5% by weight.

In case the amount of the metal salt derivative is too small, the intended object of the present invention cannot be attained. In case the amount of the metal salt derivative is too large, the mechanical properties of the filaments are degraded.

According to this invention there are provided polyester filaments having an excellent water-absorbing property and its excellent retainability. Reasons why such excellent effects are attained in accordance with the present invention have not been completely elucidated. Only blending of a polyalkylene ether and a metal salt derivative into filaments does not result in manifestation of any water-absorbing property. The synergistic action of fine pores and the polyalkylene ether and metal salt derivative contained in filaments produces the abovementioned effects.

Further, the filaments of this invention retain excellent physical properties inherent to polyester fibers and possess an excellent antistatic property at the same time.

This invention will be now detailed by referring to examples.

In examples the "parts" indicate "parts by weight." The analysis of the polyalkylene ether component was conducted in accordance with the method of Robert (Robert, J. Levins and Robert, M. Ikeda, *Analy. Chem.* 37, 671 (1965)) after decomposing the polymers with aminopropanol and neutralizing the same with acetic acid.

The analysis of the alkali metal sulfonate derivative was conducted by a method comprising depolymerizing the polymers with ethylene glycol, forming an aqueous solution of the depolymerized polymers, making the solution acidic with sulfuric acid, adding methylene blue thereto, extracting the resulting complex and subjecting it to colorimetric determination.

The amount incorporated of the derivative of a metal salt of a carboxylic, phosphonic or sulfonic acid was determined by the analysis of the metal content according to the atomic absorptiometric method.

The amount incorporated of the di- or mono-metal salt of phosphoric or phosphorous acid was determined by the analysis of the metal content according to the atomic absorptiometric method.

The inherent viscosity of the polymer was measured in o-chlorophenol at 25° C.

The evaluation of physical properties of filaments was based on CR values of wooly-processed yarns. CR values are values indicating the crimp retainability of the processed yarns. Higher values mean that yarns are more excellent in the crimp retainability and the bulkiness. The measurement of CR values is conducted in the following manner:

The sample is subjected to a boiling water treatment under a load of zero for 5 minutes. Then, the sample is taken out from boiling water, thrown into water and allowed to stand therein for 1 minute under a load of 0.1 g./d. The length (L_1) of the sample was measured. Then, the sample was taken out from water and allowed to stand under a load of 0.02 g./d. for 30 seconds. The length (L_2) of the sample was measured again. The CR value of the sample was calculated by the following equation:

$$\text{CR Value} = \frac{L_1 - L_2}{L_1} \times 100$$

The heat resistance was evaluated based on changes in color of the sample when it was allowed to stand still in a hot air drier maintained at 180° C. for 5 hours.

The coloration was evaluated based on b values measured by employing a Hunter-type color machine of Japan Color Machine Co. (a high positive b value means an increase in coloration in yellow).

The evaluation of the water-absorbing property was conducted in the following manner:

The sample was allowed to stand at 20° C. and a relative humidity of 65% for 24 hours. Then, three sheets of the sample were piled up. Thereafter, 30 μ l. of water was dropped onto the piled sheets and the period of time from the initiation of the dropping to the point when any reflecting light from the surface of water having expanded on the sample was not observed (the time being called "water absorption time") was measured. A smaller value of the water absorption time means a higher water-absorbing property of the sample.

The washing treatment was conducted in the following manner:

15 liters of water at 40° C. was filled in a washing machine of an automatic reverser type of Toshiba Electric Co. and 26 g. of an anionic, weakly alkaline soap ("Zab" of Kao Soap Co.) was added thereto. The washing was carried out for 15 minutes and the washed sample was rinsed for 15 minutes in flowing clean water.

FIG. 13 illustrates an apparatus in use for another evaluation of filaments. More specifically, the apparatus is used for evaluation of the water-absorbing property of knitted products. In FIG. 13, the numerical reference 1 indicates a fine tube containing water therein, and the reference numeral 2 designates a water pool connected with the fine tube 1. The numeral reference 3 indicates

The oozing water is absorbed in the sample 4 and then released into the air through the sample 4. In case the sample has an excellent water-absorbing property, the amount of water passing through the fine tube 1, water pool 2, unglazed plate 3 and sample 4 should be great. Therefore, the amount consumed of water was read from the scale on the fine tube 1, and based on the read value the water-absorbing property was evaluated. In FIG. 13, the reference numeral 6 represents a water supply tank.

FIG. 14 is a graph illustrating the results of the actual measurements made on several samples by employing the apparatus of FIG. 13. In FIG. 14, the ordinate denotes the amount consumed (cc.) of water and the abscission represents the time (minutes).

15 EXAMPLE 1 AND COMPARATIVE EXAMPLE 1

Polyethylene terephthalate (A) of an intrinsic viscosity of 0.660 obtained by a customary method was weighed at 295° C. by a gear pump and then fed to a 20 kneading screw portion heated at 285° C. A 2:1 mixture (B) of polyethylene glycol having a number average molecular weight of 20,000 and sodium dodecylbenzenesulfonate was weighed at 85° C. by a gear pump and fed to the kneading screw portion heated at 285° C.

25 The mixing ratio of (A):(B) was 92.5:7.5. The mixture was transferred from the kneading screw portion to a spinneret portion while being kept in the molten state. Then, the mixture was spun at a rate of 30 g./min. through a spinneret having 36 holes of a diameter of a 30 0.23 mm. and taken up at a rate of 1000 m./min. to obtain undrawn filaments. Then, the undrawn filaments were drawn at a draw ratio of 3.66 at a speed of 400 m./min. by means of a hot pin maintained at 100° C.

35 The resulting drawn filaments were characterized by a fineness of 75.1 d., a strength of 4.8 g./d., an elongation of 27.2% and a boiling water shrinkage of 11.5%.

Two of the so obtained filaments were gathered together and subjected to a wooly-processing at a yarn feed rate of 49.8 m./min., and a take-up rate of 44.0 m./min. with the use of a spindle rotating at 175,000 r.p.m. and a hot plate maintained at 205° C. Thus, there was obtained a wooly-processed yarn having a strength of 4.3 g./d., an elongation of 31.5% and a CR value (crimp retaining property) of 35.6%.

40 A knitted cloth of a weight of $15-18 \times 10^{-3}$ gm./cm.² was formed from the so obtained wooly-processed yarn. Then, the knitted cloth was scoured at 80° C. for 20 minutes under the conditions of a cleanser of 2 g./liter, soda ash of 1 g./liter and a bath ratio of 1:100. Further, the knitted cloth was treated with a 0.3 N aqueous solution of sodium hydroxide at a bath ratio of 1:100 for 20 minutes at the boiling point of the solution. Before and after the above alkali treatment, the weight decrease ratio, and the amounts of polyethylene glycol and sodium dodecylbenzenesulfonate in the knitted cloth were measured. The results are shown in Table 1 below.

TABLE 1

	Weight decrease ratio, percent	Amount of polyethylene glycol, percent	Amount of sodium dodecylbenzenesulfonate, percent
Comparative Example 1 (before alkali treatment)...	0	4.9	2.5
Example 1 (after alkali treatment).....	8.5	1.8	1.1

an unglazed plate adhering closely to water, and the reference numeral 4 represents a knitted product sample on which a perforated plate 5 formed of polymethyl methacrylate is placed so as to regulate the form of the sample. Air is blown to the sample with an angle of 45° with respect to the sample surface at a rate of 0.5 m./sec. by means of an air blaster 6. The atmosphere is maintained at 20° C. and a relative humidity of 65%. The water in the fine tube 1 and the water pool 2 rises and oozes out on the surface of the unglazed plate 3 in such a manner as if the sweat comes out from the human body.

65 Optical microscopic photos illustrating the sides of the drawn yarn before the scouring and alkali treatments and of the drawn yarn after said treatments are shown in FIGS. 1 and 2. FIG. 3 is an electromicroscopic photo of the yarn of FIG. 1 after it has been dyed with osmium tetroxide and then dissolved. FIG. 4 is an electromicroscopic photo of the yarn of FIG. 2 after it has been dyed with osmium tetroxide and then dissolved. From the results shown in Table 1, and FIGS. 1 to 4 it is seen that in the yarn before the alkaline treatment the polyethylene glycol was incorporated in the form of stripes

and that a part of the polyethylene glycol corresponding to 3.1% of the total yarn was stripped off by the alkali treatment to form fine pores. It is also seen that in addition to the polyethylene glycol and sodium dodecylbenzenesulfonate, the polyethylene terephthalate per se was stripped off in an amount of 4.0% by the alkali treatment and hence, the yarn was made thinner and the pores were expanded from their interiors. From FIG. 4 it is also seen that the diameter of the pore was about 0.1μ and the length-to-diameter ratio was greater than 10.

With respect to the knitted cloth of the yarn before the alkali treatment and the knitted cloth of the yarn after the alkali treatment, the water-absorbing property was measured. The results are shown in Table 2 below.

TABLE 2

	Before washing	After 10 washings	After 50 washings
Comparative Example 1 (before alkali treatment).....	More than 10 minutes.	More than 10 minutes...	More than 10 minutes.
Example 1 (after alkali treatment).....	Less than one second...	Less than one second...	Less than one second.

From the results shown in Table 2 it is seen that even filaments containing polyethylene glycol and sodium

5 These examples are given to show what phenomena are brought about by changing the amounts incorporated of polyethylene glycol and sodium dodecylbenzenesulfonate in the polyester of Example 1.

10 The experiments were conducted in the same manner as in Example 1 except changing the mixing ratio of polyethylene glycol and sodium dodecylbenzenesulfonate, the incorporation ratio of the mixture of polyethylene glycol and sodium dodecylbenzenesulfonate to polyethylene terephthalate, or the amounts of polyethylene glycol and

sodium dodecylbenzenesulfonate incorporated into the polyester. The results are shown in Table 5 below.

TABLE 5

	Comparative Example 2	Comparative Example 3	Example 2	Comparative Example 4	Comparative Example 5
Amount incorporated of polyethylene glycol (percent).....	5.0	15.0	5.0	5.0	1.0
Amount incorporated of sodium dodecylbenzenesulfonate (percent).....	0	0	5.0	10.0	1.0
Properties of woolly-processed yarn:					
Strength (g./d.).....	4.5	3.9	4.4	3.8	4.6

Heat resistance after alkali treatment (change in <i>b</i> value).....	+1.9	+3.6	+2.1	+7.7	+1.8

dodecylbenzenesulfonate cannot possess a water-absorbing property unless they have fine pores therein.

Table 3 shows the results of the measurement of the heat resistance of the knitted cloths of the yarn before the alkali treatment and of the yarn after the alkali treatment.

TABLE 3

Example No.:	Heat resistance (change in <i>b</i> value)
Comparative Example 1 (before alkali treatment).....	+2.0
Example 1 (after alkali treatment).....	+1.8

For comparison sake, properties of ordinary polyester filaments (control) prepared without addition of polyethylene glycol and sodium dodecylbenzenesulfonate were examined. The spinning, drawing, woolly-processing, knitting and alkali treatment were conducted in the same manner as described above. The drawn yarn was characterized by a fineness of 74.9 d., a strength of 4.7 g./d., and elongation of 27.3% and a boiling water shrinkage of 11.3%. The woolly-processed yarn was characterized by a strength of 4.5 g./d., an elongation of 33.4% and a CR value of 35.6%, and the weight decrease ratio by the alkali treatment was 2.3%. The water-absorbing property of the knitted cloth was as follows:

TABLE 4

	Before washing	After 10 washings	After 50 washings
Before alkali treatment.....	More than 10 minutes...	More than 10 minutes...	More than 10 minutes.
After alkali treatment.....	5 minutes	do	do

The heat resistance expressed in terms of the change in *b* value of the knitted was +1.5 either before or after the alkali treatment.

From the results shown in Table 5 the following matters can be seen.

As in the case of Comparative Example 2, the filaments 45 containing polyethylene glycol and having pores therein but being free of sodium dodecylbenzenesulfonate are inferior in washing resistance of the water-absorbing property. As in the case of Comparative Example 3, even if the amount of polyethylene glycol is increased in Comparative 50 Example 2, the washing resistance of the water-absorbing property is not improved, and moreover the heat resistance and the CR value of the processed yarn are lowered. As in the case of Comparative Example 4, in case the amount of sodium dodecylbenzenesulfonate is too large, the CR 55 value of the processed yarn is low and the heat resistance is degraded. As in Comparative Example 5, even if filaments contain polyethylene glycol and sodium dodecylbenzenesulfonate and the weight decrease is observed after 60 the alkali treatment, a sufficient water-absorbing property is not imparted to the filaments when the weight decrease is due only to the surface falling and the polyethylene glycol contained in the form of stripes inside the filaments is not extracted. Thus, it is seen that the results given in 65 Table 5 demonstrate clearly the effects of the present invention.

COMPARATIVE EXAMPLE 6

This example is given to show that a sufficient water-75 absorbing property is not given to filaments containing only

an alkali metal sulfonate derivative, filaments obtained by subjecting the above filaments to an alkaline treatment and filaments containing an alkali metal sulfonate derivative and having fine pores therein.

To polyethylene terephthalate of Example 1, 2.5% of sodium dodecylbenzenesulfonate was added after completion of the polymerization. Thus, there was obtained a polymer having an intrinsic viscosity of 0.655.

The so obtained polymer (A) was weighed at 295°C. by means of a gear pump and fed to a kneading screw portion heated at 285°C. Polystyrene (B) ("Styron 666", product of Asahi Dow Chemical Industry Co.) was weighed at 180°C. by means of a gear pump and fed to the kneading screw portion heated at 285°C. The mixing ratio of (A) to (B) was 90:10.

Thereafter, the spinning, drawing, processing and knitting were conducted in the same manner as in Example 1, and then the polystyrene was eluted with trichlene at its boiling point. The weight decrease ratio was 9.1% at this treatment. It was confirmed that the filaments after the elution treatment contained sodium dodecylbenzenesulfonate in an amount of 1.0%. Thus, it is seen that the polystyrene portion incompatible with the polyester had been eluted out from the filaments and there were contained fine pores in the filaments. The water-absorbing property of the so treated filaments was characterized by 3 minutes before washing, more than 10 minutes after 10

Prior to the initiation of the preparation of polyethylene terephthalate, polyethylene glycol having a molecular weight of 20,000 was added to the polymerization system in an amount of 3.1% by weight based on the resulting polymer, and 2.5% by weight of sodium dodecylbenzenesulfonate was added after completion of the polymerization. Thus, there was obtained a polymer having an intrinsic viscosity of 0.663. In the same manner as in Comparative Example 6, the polymer was blend-spun with polystyrene, drawn, processed, knitted and treated with trichlene. After the trichlene treatment the amount incorporated of polyethylene glycol was 3.0%, and the amount incorporated of sodium dodecylbenzenesulfonate was 1.0%. The polystyrene in an amount of 9.0% was eluted out and fine pores were formed.

The water-absorbing property of the product was characterized by 1.0 second after 50 washings.

EXAMPLES 4 TO 7 AND COMPARATIVE EXAMPLES 7 TO 8

These examples are given to show what changes are brought about when the class of the polyalkylene ether to be incorporated is varied.

The experiments were conducted in the same manner as in Example 1 except changing the class of the polyalkylene ether to be incorporated. The results of the experiments are shown in Table 6 below.

TABLE 6

	Example 4	Comparative Example 7	Example 5	Example 6	Comparative Example 8	Example 7
Class of polyalkylene.	Polypropylene glycol. ¹	Polyethylene glycol. ²	Polyethylene glycol. ¹	Ethylene oxide/pro-pylene oxide co-polymer. ³	Polyethylene glycol. ⁴	Polyethylene glycol. ⁵

¹ Having a molecular weight of 6,000.

² Having a molecular weight of 600.

³ Having a molecular weight of 21,000 (copolymerization ratio = 1:1).

⁴ Both terminal ends of which are blocked with $-\text{OCH}_3$ (molecular weight = 16,000).

⁵ One terminal end of which is blocked with phosphoric acid (molecular weight = 10,000).

washings and more than 10 minutes after 50 washings. The water-absorbing property of a knitted product of the filaments prepared without addition of polystyrene by conducting the spinning, drawing, processing and knitting in the same manner as above was characterized by more than 10 minutes before washing. The water-absorbing property of a knitted product obtained by subjecting the above mentioned knitted product to an alkali treatment with a weight decrease ratio of 6.1% was characterized by 3 minutes before washing and more than 10 minutes after 10 washings. In this alkali-treated knitted product the content of sodium dodecylbenzenesulfonate was 1.0%, and fine pores were not formed in the filaments because sodium dodecylbenzenesulfonate was compatible with the polyester.

EXAMPLE 3

This example is given to show that even when fine pores are formed by a method different from the method adopted in Example 1, the effects of the present invention can be fully achieved.

From the results shown in Table 6 the following matters can be seen:

In Comparative Example 7, since the polyethylene glycol was not selectively eluted and fine pores were not formed, the filaments did not exhibit a sufficient water-absorbing property. In comparative Example 8, since the content of the polyalkylene ether in the filaments was too small, the filaments did not exhibit a sufficient water-absorbing property. Thus, it is seen that the results given in Table 6 demonstrate clearly the effects attained by the present invention.

EXAMPLES 8 AND 9

These examples are given to show what changes are brought about by varying the class of the alkali metal sulfonate derivative in Example 1.

The experiments were conducted in the same manner as in Example 1 except using other alkali metal sulfonate derivatives instead of sodium dodecylbenzenesulfonate.

The results are shown in Table 7 below.

TABLE 7

	Example 8	Example 9
Class of alkali metal sulfonate derivative	Sodium nonyl-benzenesulfonate	Potassium dodecylbenzenesulfonate
Properties of processed yarn:		
Strength (g/d.)	4.2	4.1
Elongation (percent)	34.2	33.6
CR value (percent)	36.0	34.8
After alkali treatment:		
Weight decrease ratio (percent)	8.3	8.5
Amount incorporated of polyethylene glycol (percent)	1.6	1.3
Amount incorporated of alkali metal sulfonate derivative (percent)	1.0	0.9
Water-absorbing property:		
Before washing	Less than 1 second	Less than 1 second
10 washings	do	Do
50 washings	do	1 second
Heat resistance (change in <i>b</i> value)	+2.0	+2.3

EXAMPLES 10 TO 11 AND COMPARATIVE EXAMPLES 9 TO 10

These examples are given to show what changes are brought about by varying the mixing method of polyethylene glycol (X) and sodium dodecylbenzenesulfonate (Y) in Example 1.

EXAMPLES 12 TO 13 AND COMPARATIVE EXAMPLES 11 TO 15

Frictional electrification voltages of various knitted products were measured at 20° C. and a relative humidity of 43% by means of a rotary static tester. The results are shown in Table 9.

TABLE 9

Sample	Frictional electrification voltage (v.)
Example 12	2,300
Comparative Example 11	9,800
Comparative Example 12	7,000
Comparative Example 13	6,500
Example 13	2,100
Comparative Example 14	8,100
Comparative Example 15	7,200

In these examples the amounts mixed of (X) and (Y) are the same as in Example 1. The drawn yarns were of 40 75 deniers and 36 filaments. The spinning and drawing conditions were made as equal to those of Example 1 as possible. The processing, knitting and alkali treatment conditions were quite the same as those adopted in 45 Example 1.

The results are shown in Table 8 below.

It is seen that the results given in Table 9 clearly demonstrate the effects attained by the present invention.

EXAMPLE 14 AND COMPARATIVE EXAMPLES 16 TO 18

These examples are given to show the correspondence of the water-absorption time used as the criterion for evaluation of the water-absorbing property to the stuffy uncomfortable feeling of wearers.

TABLE 8

	Example 10	Example 11	Comparative Example 9	Comparative Example 10
Mixing method	(Y) was added to the polymerization vessel and mixed with (X) by extruder, followed by spinning.	(X) and (Y) were added to the polymerization vessel after polymerization.	(X) was added to the polymerization vessel, and (Y) was incorporated by extruder.	(X) was added to the polymerization vessel before polymerization, and (Y) was added to the vessel after polymerization.
Properties of processed yarn:				
Strength (g/d.)	4.4	4.3	4.4	4.2
Elongation (percent)	31.6	32.3	31.6	32.6
CR value (percent)	34.3	35.6	32.6	36.2
After alkali treatment:				
Weight decrease ratio (percent)	8.8	8.2	7.3	6.9
Amount incorporated of polyethylene glycol (percent)	1.7	1.5	4.8	4.9
Amount incorporated of sodium dodecylbenzenesulfonate (percent)	1.2	1.3	1.1	1.3
Water-absorbing property:				
Before washing	Less than 1 second	Less than 1 second	3 minutes	4 minutes
10 washings	do	1 second	More than 10 minutes	More than 10 minutes
50 washings	1 second	10 seconds	do	Do
Heat resistance (change in <i>b</i> value)	+1.7	+1.9	+2.3	+2.6

In comparative examples, since (X) was copolymerized with the polyester and hence (X) was not selectively eluted at the alkali treatment, fine pores were not formed and filaments having a water-absorbing property could not be obtained.

With respect to each of a knit underwear of the product of Example 1, a knit underwear of the control product described in Example 1, a knit underwear of Comparative Example 2, and a commercially available knit under-

wear of pure cotton having a weight of 17×10^{-3} g./cm.², 10 men having an age of 20 to 25 years put on such knit underwear and were allowed to stay for 3 hours at a room maintained constantly at 27° C. and a relative humidity

treatment, the weight decrease, the amount of polyethylene glycol and the amount of disodium nonylbenzenephosphonate were measured. The results are shown in Table 11 below.

TABLE 11

	Weight decrease ratio, percent	Amount of polyethylene glycol, percent	Amount of disodium nonylbenzenephosphonate, percent
Comparative Example 19 (before alkali treatment)	0	5.0	2.4
Example 15 (after alkali treatment)	8.2	1.9	1.0

of 65%, and the number of men complaining of a stuffy uncomfortable feeling was recorded. The tests were conducted with respect to either the underwears before washing or the underwears after 50 washings. The results are shown in Table 10.

Comparative Example 18	Underwear of pure cotton	1

EXAMPLE 15 AND COMPARATIVE EXAMPLE 19

Polyethylene terephthalate (A) of an intrinsic viscosity of 0.660 containing 0.5% of titanium oxide as a delustering agent and obtained by a customary method was weighed at 295° C. by means of a gear pump, and then fed to a kneading screw portion heated at 285° C. A 2:1 mixture (B) of polyethylene glycol having a number average molecular weight of 20,000 and disodium nonylbenzenephosphonate was weighed at 85° C. by means of a gear pump and fed to the kneading screw portion heated at 285° C.

The mixing ratio of (A) and (B) was 92.5:7.5. The mixture was transferred from the kneading screw portion to a spinneret portion while being kept in the molten state. Then, the molten mixture was spun at a rate of 30 g./min. through a spinneret having 36 nozzles of a 0.23 mm. diameter. The extrudate was taken up at a rate of 1000 m./min. to obtain undrawn filaments. Thereafter, the filaments were drawn at a draw ratio of 3.66 at a

acterized by a fineness of 73.8 d., strength of 4.9 g./d., an elongation of 26.4% and a boiling water shrinkage of 11.5%. The wooly-processed yarn was characterized by a strength of 4.5 g./d., an elongation of 32.8% and a CR value of 36.3%. The weight decrease ratio by the alkali treatment was 2.2%. The water-absorbing property of the knitted cloth was as follows:

TABLE 14

	Before washing	After 10 washings	After 50 washings
Before alkali treatment.....	More than 10 minutes.	More than 10 minutes.	More than 10 minutes.
After alkali treatment.....	5 minutes.....	do.....	Do.

The heat resistance expressed in terms of the change in *b* value of the knitted cloth was +1.5 either before or after the alkali treatment.

EXAMPLES 16 AND COMPARATIVE EXAMPLES 20 TO 23

These examples are given to show what phenomena are brought about by changing the amounts incorporated of polyethylene glycol and disodium nonylbenzenephosphonate in the polyester of Example 15.

The experiments were conducted in the same manner as described in Example 15 except changing the mixing ratio of polyethylene glycol and disodium nonylbenzenephosphonate, the incorporation ratio of the mixture of polyethylene glycol and disodium nonylbenzenephosphonate to polyethylene terephthalate, or the amounts of polyethylene glycol and disodium nonylbenzenephosphonate incorporated in the polyester. The results are shown in Table 15 below.

This example is given to show that a sufficient water-absorbing property is not imparted to filaments containing only disodium nonylbenzenephosphonate, filaments obtained by subjecting the above filaments to an alkali treat-

ment, and filaments containing disodium nonylbenzenephosphonate and having fine pores therein.

To polyethylene terephthalate of Example 15, 2.5% of disodium nonylbenzenephosphonate was added after completion of the polymerization. Thus, there was obtained a polymer having an intrinsic viscosity of 0.657.

The so obtained polymer (A) was weighed at 295°C. by means of a gear pump and fed to a kneading screw portion heated at 285°C. Polystyrene (B) ("Styron 666", product of Asahi Dow Chemical Industry Co.) was weighed at 180°C. by means of a gear pump and fed to the kneading screw portion heated at 285°C. The mixing ratio of (A) to (B) was 90:10.

Thereafter, the spinning, drawing, processing and knitting were conducted in the same manner as in Example 15, and then the polystyrene was eluted with trichlene at its boiling point. The weight decrease ratio was 9.0% at this elution treatment. It was confirmed that the fila-

From the results shown in Table 15, the following matters can be seen:

As in the case of Comparative Example 20, the filaments containing polyethylene glycol and having pores therein but being free of disodium nonylbenzenephosphonate are inferior in washing resistance of the water-absorbing property. As in the case of Comparative Example 21, even if the amount of polyethylene glycol is increased in Comparative Example 20, the washing resistance of the water-absorbing property is not improved, and moreover the heat resistance and the CR value of the processed yarn are lowered. As in the case of Comparative Example 22, in case the amount of disodium nonylbenzenephosphonate is too large, the CR value of the processed yarn is low and the heat resistance is degraded. As in the case of Comparative Example 23, even if filaments contain polyethylene glycol and disodium nonylbenzenephosphonate and the weight decrease is observed after the alkali treatment, a sufficient water-absorbing property is not imparted to the filaments when the weight decrease is due only to the surface falling and the polyethylene glycol contained in the form of stripes inside the filaments is not extracted. Thus, it is seen that the results given in Table 15 demonstrate clearly the effects of the present invention.

ments after the elution treatment contained disodium nonylbenzenephosphonate in an amount of 1.0%. Thus, it is seen that the polystyrene portion incompatible with the polyester had been eluted out from the filaments and there were contained fine pores in the filaments. The water-absorbing property of the so treated filaments was characterized by 4 minutes before washing, more than 10 minutes after 10 washings and more than 10 minutes after 50 washings. The water-absorbing property of a knitted product of the filaments prepared without addition of polystyrene by conducting the spinning, drawing, processing and knitting in the same manner as above was characterized by more than 10 minutes before washing. The water-absorbing property of a knitting product obtained by subjecting the above mentioned knitted product to an alkali treatment with a weight decrease ratio of 6.1% was characterized by 4 minutes before washing and more than 10 minutes after 10 washings. In this alkali-treated knitted product the content of disodium nonylbenzenephosphonate was 1.3%, and fine pores were not present in the filaments because disodium nonylbenzenephosphonate was compatible with the polyester.

EXAMPLE 17

This example is given to show that even when fine pores are formed by a method different from the method

adopted in Example 15, the effects of the present invention can be fully achieved.

Prior to the initiation of the preparation of polyethylene terephthalate, polyethylene glycol having a molecular weight of 20,000 was added to the polymerization system in an amount of 3.1% by weight, and 2.5% by weight of sodium stearate was added after completion of the polymerization. Thus, there was obtained polymer having an intrinsic viscosity of 0.663. In the same manner as in Comparative Example 24 the polymer was blend-spun with polystyrene, drawn, processed, knitted and treated with trichlene. After the trichlene treatment the amount incorporated of polyethylene glycol was 2.9%, and the amount incorporated of sodium stearate was 1.1%. The polystyrene in an amount of 9.0% was eluted out and fine pores were formed in the filaments.

The water-absorbing property of the product was characterized by 8 seconds after 50 washings.

EXAMPLES 18 TO 21 AND COMPARATIVE EXAMPLES 25 TO 26

These examples are given to show what changes are brought about when the class of the polyalkylene ether to

From the results shown in Table 16, the following matters can be seen:

In Comparative Example 25, since the polyethylene glycol was not selectively eluted and fine pores were not formed in the filaments, they do not exhibit a sufficient water-absorbing property. In Comparative Example 26, since the content of the polyalkylene ether in the filaments was too small, the filaments do not exhibit a sufficient water-absorbing property. Thus, it is seen that the results given in Table 16 demonstrate clearly the effects attained by the present invention.

EXAMPLES 22 TO 24

These examples are given to show what changes are brought about by varying the class of the metal salt derivative in Example 15.

The experiments were conducted in the same manner as in Example 15 except using other metal salt derivative instead of disodium nonylbenzenephosphonate.

The results are shown in Table 17 below.

EXAMPLE 27 AND COMPARATIVE EXAMPLES 32 TO 34

These examples are given to show the correspondence of the water-absorbing time used as the criterion for evaluation of the water-absorbing property to the stuffy uncomfortable feeling of wearers.

With respect to each of a knit underwear of the product of Example 15, a knit underwear of the control products described in Example 15, a knit underwear of the product of Comparative Example 20, and a commercially available knit underwear of pure cotton having a weight of 17×10^{-3} g./cm.², 10 men having an age of 20 to 25 years put on such knit underwear and were allowed to stay for 3 hours at a room maintained constantly at 27° C. and a relative humidity of 65%, and the number of men complaining of a stuffy uncomfortable feeling was recorded. The tests were conducted with respect to either the underwears before washing or the underwears after 50 washings. The results are shown in Table 19.

15 speed of 400 m./min. by means of a hot pin heated at 100° C.

The resulting drawn filaments were characterized by a fineness of 74.7 d., a strength of 4.9 g./d., an elongation of 28.1% and a boiling water shrinkage of 13.1%. Two 20 of the drawn filaments were gathered and then subjected to a wooly-processing treatment at a yarn feed rate of 49.8 m./min., a take-up rate of 4.40 m./min. and a hot plate temperature of 205° C. with the use of a spindle rotating at 175,000 r.p.m. The so obtained wooly-processed 25 yarn were characterized by a strength of 4.4 g./d., an elongation of 30.3%, and a CR value (crimp retaining property) of 34.8%. A knitted cloth having a weight of $15-18 \times 10^{-3}$ g./cm.² was prepared from the above 30 wooly-processed yarn, and it was scoured at 80° C. for 20 minutes under the conditions of a cleanser of 2 g./liter, soda ash of 1 g./liter and a bath ratio of 1:100. Then, the scoured cloth was treated for 20 minutes with a 35 0.3 N aqueous solution of sodium hydroxide at the boiling point of the solution.

EXAMPLE 28 AND COMPARATIVE EXAMPLE 35

Polyethylene terephthalate (A) of an intrinsic viscosity of 0.660 containing 0.5% of titanium oxide as a delustering agent and obtained by a customary method

Before and after the said alkali treatment, the weight decrease ratio, the amount of polyethylene glycol and the amount of disodium nonylphenolphosphoric acid ester were measured. The results are shown in Table 20 below.

TABLE 20

	Weight decrease ratio, percent	Amount of polyethylene glycol, percent	Amount of disodium nonylphenolphosphoric acid ester, percent
Comparative Example 35 (before alkali treatment)	0	4.9	2.5
Example 28 (after alkali treatment)	8.3	1.7	1.0

was weighed at 295° C. by means of a gear pump, and then fed to a kneading screw portion heated at 285° C. A 2:1 mixture (B) of polyethylene glycol having a number average molecular weight of 20,000 and disodium nonylphenolphosphoric acid ester was weighed at 85° C. by means of a gear pump, and then fed to the kneading screw portion heated at 285° C.

The mixing ratio of (A) and (B) was 92.5:7.5. The mixture was transferred from the kneading screw portion to a spinneret portion while being kept in the molten state. Then, the molten mixture was spun at a rate of 30 g./min. through a spinneret having 36 nozzles of a 0.23 mm. diameter. The extrudate was taken up at a rate

65 of the drawn yarn after the scouring and alkali treatments were shown in FIGS. 9 and 10. FIG. 11 is an electromicroscopic photo of FIG. 9, after it has been dyed with osmium tetroxide and dissolved. FIG. 12 is an electromicroscopic photo of the yarn of FIG. 10, after 70 it has been dyed with osmium tetroxide and dissolved.

From the results given in Table 20, and FIGS. 9 to 12, it is seen that in the yarn before the alkali treatment the polyethylene glycol was incorporated in the form of stripes and that a part of the polyethylene glycol corresponding to 3.2% of the total yarn was stripped off by the

23

alkali treatment to form fine pores. It is also seen that in addition to the polyethylene glycol and disodium nonylphenolphosphoric acid ester, the polyethylene terephthalate per se was stripped off in an amount of 3.6% by the alkali treatment, and hence, the yarn was made thinner and the pores were expanded from their interior. From FIG. 12, it is observed that the diameter of the pore was about 0.1μ and the length-to-diameter ratio was greater than 10.

With respect to the knitted cloth of the yarn before the alkali treatment and the knitted cloth of the yarn after the alkali treatment, the water-absorbing property was measured. The results are shown in Table 21 below.

absorbing property unless they have fine pores therein.

Table 22 shows the results of the measurement of the heat resistance of the knitted clothes of the yarn before the alkali treatment and of the yarn after the alkali treatment.

TABLE 22

Example No:	Heat resistance (change in <i>b</i> value)
Comparative Example 35 (before alkali treatment).....	+2.1.....
Example 28 (after alkali treatment).....	+1.9.....

For comparison sake, properties of ordinary polyester filaments (control) prepared without addition of polyethylene glycol and disodium nonylphenolphosphoric acid ester were examined. The spinning, drawing, wooly-processing, knitting and alkali treatment were conducted in the same manner as described above. The drawn yarn was characterized by a fineness of 74.9 d., a strength of 4.7 g./d., an elongation of 27.5% and a boiling water shrinkage of 12.0%. The wooly-processed yarn was characterized by a strength of 4.5 g./d., an elongation of 33.5% and a CR value of 37.2%. The weight decrease ratio by the alkali treatment was 2.2%. The water-absorbing property of the knitted cloth was as follows.

From the results shown in Table 24, the following matters can be seen:

As in the case of Comparative Example 36, the filaments containing polyethylene glycol and having pores therein but being free of disodium nonylphenolphosphoric acid ester are inferior in washing resistance of the water-absorbing property. As in the case of Comparative Example 37, even if the amount of polyethylene glycol was increased in Comparative Example 36, the washing resistance of the water-absorbing property is not improved, and moreover the heat resistance and the CR value of the processed yarn are lowered. As in the case of Comparative Example 38, in case the amount of disodium nonylphenolphosphoric acid ester is too large, the CR value of the processed yarn is low and the heat resistance is degraded. As in the case of Comparative Example 39, even if filaments contain polyethylene glycol and disodium nonylphenolphosphoric acid ester and the weight decrease is observed after the alkali treatment, a sufficient water-absorbing property is not given to the filaments when the weight decrease is due only to the surface falling and the polyethylene glycol contained in the form of stripes inside the filaments is not extracted. Thus, it is seen that the results given in Table 24 demonstrate clearly the effects of the present invention.

TABLE 23

	Before washing	After 10 washings	After 50 washings

After alkali treatment.....	5 minutes.....	do.....	Do.....

The heat resistance expressed in terms of the change in *b* value of the knitted cloth was +1.5 either before or after the alkali treatment.

24

EXAMPLE 29 AND COMPARATIVE EXAMPLES
36 TO 39

These examples were given to show what phenomena are brought about by changing the amounts incorporated of polyethylene glycol and disodium nonylphenolphosphoric acid ester in the polyester of Example 28.

The experiments were conducted in the same manner as in Example 28 except changing the mixing ratio of polyethylene glycol and disodium nonylphenolphosphoric acid ester, the incorporation ratio of the mixture of polyethylene glycol and disodium nonylphenolphosphoric acid ester to polyethylene terephthalate or the amounts

COMPARATIVE EXAMPLE 40

This example is given to show that a sufficient water-absorbing property is not imparted to filaments contain-

ing only disodium nonylphenylphosphoric acid ester, filaments obtained by subjecting the above filaments to an alkali treatment, and filaments containing disodium nonylphenylphosphoric acid ester and having fine pores therein.

To polyethylene terephthalate of Example 28, 2.5% of disodium nonylphenylphosphoric acid ester was added after completion of the polymerization. Thus, there was obtained a polymer having an intrinsic viscosity of 0.658.

The so obtained polymer (A) was weighed at 295° C. by means of a gear pump and fed to a kneading screw portion heated at 285° C. Polystyrene (B) ("Styron 666," product of Asahi Dow Chemical Industry Co.) was weighed at 180° C. by means of a gear pump and fed to the kneading screw portion heated at 285° C. The mixing ratio of (A) to (B) was 90:10.

Thereafter, the spinning, drawing, processing and knitting were conducted in the same manner as in Example 28, and then the polystyrene was eluted with trichlene at its boiling point. The weight decrease ratio was 9.0% at this elution treatment. It was confirmed that the filaments after the elution treatment contained disodium nonylphenylphosphoric acid ester in an amount of 1.1%. Thus it is seen that the polystyrene portion incompatible with the polyester had been eluted out from the filaments, and there were formed fine pores in the filaments. The water-absorbing property of the so treated filaments was characterized by 3 minutes before washing, more than

Prior to the initiation of the preparation of polyethylene terephthalate, polyethylene glycol having a molecular weight of 20,000 was added to the polymerization system in an amount of 3.1% by weight, and 2.5% by weight of monopotassium di(dodecylalcohol)phosphorous acid ester was added after completion of the polymerization. Thus, there was obtained a polymer having an intrinsic viscosity of 0.663. In the same manner as in Comparative Example 40 the polymer was blend-spun with polystyrene, drawn, processed, knitted and treated with trichlene. After the trichlene treatment the amount incorporated of polyethylene glycol was 3.1% and the amount incorporated of monopotassium di(dodecylalcohol)phosphorous acid ester was 1.1%. The polystyrene in an amount of 9.1% was eluted out and fine pores were formed in the filaments.

The water-absorbing property of the product was characterized by 9 seconds after 50 washings.

EXAMPLES 31 TO 34 AND COMPARATIVE EXAMPLES 41 TO 42

These examples are given to show what changes are brought about when the class of the polyalkylene ether to be incorporated is varied in Example 28.

The experiments were conducted in the same manner as in Example 28 except changing the class of the polyalkylene ether to be incorporated. The results are shown in Table 25 below.

TABLE 25

	Example 31	Comparative Example 41	Example 32	Example 33	Comparative Example 42	Example 34

¹ Having a molecular weight of 6,000.

² Having a molecular weight of 600.

³ Having a molecular weight of 21,000 (copolymerization ratio=1:1).

⁴ Both terminal ends of which are blocked with $-\text{OCH}_3$ (molecular weight=16,000).

One terminal end of which is blocked with phosphoric acid (molecular weight=10,000).

10 minutes after 10 washings and more than 10 minutes after 50 washings. The water-absorbing property of a knitted product of the filaments prepared without addition of polystyrene by conducting the spinning, drawing, processing and knitting in the same manner as above was characterized by more than 10 minutes before washing. The water-absorbing property of a knitted product obtained by subjecting the above mentioned knitted product to an alkali treatment with a weight decrease ratio of 6.2% was characterized by 4 minutes before washing and more than 10 times after 10 washings. In this alkali-treated knitted product the content of disodium nonylphenylphosphoric acid ester was 1.5%, and fine pores were not present in the filaments because disodium nonylphenylphosphoric acid ester was compatible with the polyester.

EXAMPLE 30

This example is given to show that even when fine pores are formed by a method different from the method adopted in Example 28, the effects of the present invention can be fully achieved.

From the results shown in Table 25, the following matters can be seen. In Comparative Example 41, since the polyethylene glycol was not selectively eluted and fine pores were not formed in the filaments, they do not exhibit sufficient water-absorbing property. In Comparative Example 42, since the content of the polyalkylene ether is small, the filaments do not exhibit a sufficient water-absorbing property. Thus, it is seen that the results shown in Table 25 demonstrate clearly the effects attained by the present invention.

EXAMPLES 35 TO 37

These examples are given to show what changes are brought about by varying the class of the metal salt derivative of phosphoric or phosphorous acid in Example 28.

The experiments were conducted in the same manner as in Example 28 except using other metal salt derivative

instead of disodium nonylphenylphosphoric acid ester. The results are shown in Table 26 below.

TABLE 26

	Example 35	Example 36	Example 37
